UNITED STATES PATENT OFFICE.

WILL S. JAMES, OF FORT WORTH, TEXAS.

WINDOW-FASTENER.

SPECIFICATION forming part of Letters Patent No. 629,446, dated July 25, 1899.

Application filed February 9, 1899. Serial No. 705,057. (No model.)

To all whom it may concern:

Be it known that I, WILL S. JAMES, a citizen of the United States, residing at Fort Worth, in the county of Tarrant and State of Texas, have invented a new and useful Window-Fastener, of which the following is a specification.

The invention relates to improvements in window-fasteners.

10 The object of the present invention is to improve the construction of window-fasteners and to provide a simple, inexpensive, and efficient device adapted for holding a sash at the desired adjustment and capable of being 15 readily arranged to lock the same against upward or downward movement.

20 A further object of the invention is to provide for sashes having no counterbalancing weights a device which will enable a sash to be raised freely, but which will prevent the same from dropping or moving downward.

25 The invention consists in the construction and novel combination and arrangement of parts hereinafter fully described, illustrated 30 in the accompanying drawings, and pointed out in the claims hereto appended.

35 In the drawings, Figure 1 is an elevation, partly in section, of a portion of a window provided with a device constructed in accordance with this invention. Fig. 2 is a perspective view of the locking device, the spring-actuated bolt being arranged to present upper and lower shoulders. Fig. 3 is a longitudinal sectional view of the same. Fig. 4 is 40 a detail perspective view of the casing, showing the rear face thereof. Fig. 5 is an elevation, partly in section, illustrating the modification of the invention. Fig. 6 is a transverse sectional view of the locking device 45 thereof.

Like numerals of reference designate corresponding parts in all the figures of the drawings.

50 1 designates a ratchet-strip constructed of suitable metal and provided at intervals with rectangular bends 2, forming upper and lower shoulders, which are adapted to be engaged by a spring-actuated bolt 3, and the said strip is secured to a window frame or casing adjacent to a sash by screws or other suitable fastening devices passing through perforations formed in the angular bends 2 and arranged

55 at intervals. The spring-actuated bolt 3, which is provided with a beveled engaging end 4, is arranged within a casing 5 and is provided adjacent to its engaging end with a lug or projection 6, preferably cast integral with the bolt and operating in front and rear slots 7 and 8 of the casing 5. The inner portion of the bolt is reduced to receive a coiled 60 spring, which bears against the shoulder formed by reducing the bolt and which engages the inner end of the casing, the latter being provided at that point with an interior shoulder formed by reducing the bore. 65

The front slot, which communicates with the bore, extends inward from one end of the casing, and the rear slot terminates short of such end of the casing and is provided at its inner end with oppositely-disposed branches 70 9 and 10, the former communicating with the front slot at the inner end thereof and permitting the lug or projection to be transferred from one slot to the other by partially rotating the bolt. This construction enables the 75 bolt to be given a quarter-turn to arrange its beveled edge uppermost, as shown in Fig. 1, or to arrange its flat side edges in a horizontal position to engage the shoulders of the 80 ratchet-strip for locking the sash against upward or downward movement. The other branch 10 of the inner slot forms a stop and is adapted to be engaged by the lug or projection to hold the bolt retracted and out of engagement with the ratchet-strip, so that 85 the sash may be moved freely in either direction. The slots also form convenient means for enabling the parts of the locking device to be readily assembled, and the inner end of the bolt is threaded at 11 and receives a detachable head 12, having a threaded opening and normally holding the bolt sufficiently retracted to retain the lug in the grooves and prevent the same from leaving the front slot. 90

95 In Figs. 5 and 6 is illustrated a modification of the invention, in which a round bolt 13 is employed, and this round bolt is adapted to engage perforations 14 of a ratchet-strip 15, which is provided at intervals with rectangular bends. The casing 16, which receives the 100 bolt 13, is constructed similar to the casing heretofore described, and it is provided with front and rear slots to enable the parts to be assembled. The form illustrated in Figs. 1

to 4, inclusive, is especially adapted for sashes having no counterbalancing-weights, and the other form is adapted for balance-sashes.

The invention has the following advantages: The window-fastener, which is simple and comparatively inexpensive in construction, is adapted to be readily applied to upper and lower sashes whether weighted or unbalanced. It is adapted to support a sash at the desired elevation, and it is capable of locking it against upward or downward movement. The spring-actuated bolt may be retained out of engagement with the ratchet-strip to enable the sashes of a window to move freely in either direction, and when it is disposed with its beveled edge uppermost the sound caused by the bolt riding over the shoulders will be sufficient to alarm the inmates of a room should any one attempt to raise the sash from the exterior. The slots at the front and back of the bolt-casing permit the parts to be readily assembled and separated.

Changes in the form, proportion, size, and the minor details of construction within the scope of the appended claims may be resorted to without departing from the spirit or sacrificing any of the advantages of this invention.

What is claimed is—

1. A device of the class described comprising a casing having a bore and provided at opposite sides with longitudinal slots, one of the slots being extended to one end of the casing to form an entrance and the other slot be-

ing provided at its inner end with a branch communicating with the entrance-slot, and a 35 detachable bolt adapted to engage a ratchet-strip and provided with a lug arranged to enter the said slots, substantially as described.

2. A device of the class described comprising a casing having a bore and provided at 40 opposite sides with longitudinal slots, one of the slots being extended to one end of the casing to provide an entrance, and the other slot being provided at its inner end with opposite 45 branches communicating with the entrance-slot and forming a stop, and a detachable bolt adapted to engage a ratchet-strip and provided with a lug arranged to operate in the said slots, substantially as described.

3. A device of the class described comprising a casing having a bore and provided with opposite longitudinal slots and having a transverse branch located at the inner ends of the slots, and a beveled bolt provided with a projection or lug located at a point between its 55 ends and operating in the said slots, whereby the bolt is adapted to be partially rotated, substantially as described.

In testimony that I claim the foregoing as my own I have hereto affixed my signature in 60 the presence of two witnesses.

WILL S. JAMES.
